UNITED STATES PATENT OFFICE.

LOUIS H. LARSON, OF SANTIAGO, MINNESOTA.

DITCHING MACHINE.

Application filed March 1, 1922. Serial No. 540,166.

To all whom it may concern:

Be it known that I, LOUIS H. LARSON, a citizen of the United States, resident of Santiago, county of Sherburne, State of Minnesota, have invented certain new and useful Improvements in Ditching Machines, of which the following is a specification.

My invention relates to machines adapted for digging, widening or deepening open ditches or digging tile trenches, and the primary object of the invention is to dispense with the heavy, cumbersome machines of this type in general use and provide one which will be comparatively light and easily moved from place to place.

A further and particular object is to dispense with the heavy power plant end of the machine usually necessary for counter-balancing the weight of the boom and provide a structure in which the boom is supported at both ends and the excavating bucket or dipper suspended between them.

A further object is to provide means for conveniently depositing the excavated material on either side of the ditch or trench.

A further object is to provide a frame so constructed that it will adapt itself to inequalities of the ground over which the machine may be moving.

Other objects of the invention will appear from the following detailed description.

The invention consists generally in various constructions and combinations, all as hereinafter described and particularly pointed out in the claims.

In the accompanying drawings forming part of this specification—

Figure 1 is a plan view of a ditching machine embodying my invention.

Figure 2 is a side elevation of the same, showing the dipper in position to discharge its load.

Figure 3 is a detail sectional view on the line 3—3 of Figure 2.

Figure 4 is a front elevation of the machine, the working position of the dipper being indicated by dotted lines.

Figure 5 is a detail view, showing the boom supporting carriage at the limit of its travel in one direction.

Figure 6 is a plan view showing the machine with the extension track removed to adapt it for tile trenching.

Figure 7 is a front elevation of the same, Figures 8 and 9 are details perspective

views, showing the manner of pivotally connecting the frame rails at the corners.

Figure 10 is a detail plan view of the boom and bucket operating mechanism.

Figure 11 is a detail sectional view showing the means for automatically stopping the movement of the boom supporting carriage on its track.

In the drawings, referring to Figures 1 and 2, 2 represents suitable frames having traction belts 3 mounted therein. These frames are pivotally connected at 4 with the frame 5 of the machine, which consists preferably of I-beam rails arranged to form a rectangle and having pivotal connections

at the corners to allow the rails to rock or oscillate one upon the other and permit the frame of the machine to adapt itself to inequalities of the ground over which it may be moving. Braces 7 connect the traction belt frames with the frame 5, allowing freedom of movement of the traction belt frames

on their pivots but holding them in their proper relative position. Diagonal braces 8 pivotally connect the side rails of the frame with the middle portion of the rear rails and aid in holding the parts of the frame in position. These braces also support the forward portion of the deck or platform, as shown in Figure 6.

At the rear of the main frame is a platform or deck 9 on which the power plant and operating mechanism of the machine are mounted. 10 represents a suitable motor, preferably of the internal combustion type. Drive shafts 11 having universal joints 12 therein are connected with the motor 10. From these shafts 11 drive belts 13 transmit power through a suitable differential to the traction belts 3 to propel the machine. I do not explain this driving connection in detail, as it may be modified in various ways as conditions may require and I make no claim to the same herein. It is sufficient to state that power is applied from the motor to drive the traction belts at the rear on both sides of the machine.

At the forward end of the deck 9, I provide a base plate 14 having a pivot 15 for the rear end of a boom 16 provided with wheel 17 to roll on the surface of the base plate as the boom is swung horizontally from side to side. 18 represents the excavating dipper or bucket, of any ordinary or preferred construction, having an arm 19,

105
110

a lifting bail 20, and a hinged bottom 21 normally held in its closed position by the locking device 22, commonly used on dippers of this type.

5 The boom has a horizontal extension 23 at its outer end and a cable 24 is connected to this extension at 25 and has a running connection with the bail 20 and from thence passes over a sheave 26 on the boom to a 10 drum 27 mounted preferably near the middle portion of the deck 9 and which I prefer to designate as the loading drum. A drive shaft 28 is mounted on the deck 9 and has a belt connection 29 with the motor 10 15 and a chain drive connection 30 with the drum 27. This shaft operates continuously when the motor is in motion, having preferably a friction starting clutch 31 and a clutch 32 by means of which the drive chain 20 30, loosely connected with the shaft 28, may be controlled. A roller 33 is preferably mounted on the middle portion of the boom for guiding the loading cable past the dipper arm. This cable has the function of 25 pulling the dipper through the soil to load it, as indicated by the dotted line position of the dipper and cable in Figure 2.

A drum 34, see Figure 3, is mounted in the boom and a cable 35 is attached to the 30 dipper arm and is wound on said drum. A worm gear 36 is mounted on the drum 34 and engages a worm 37 on a rod 38 having an operating crank 39 by means of which the drum 34 may be revolved to wind or 35 unwind the cable 35 and regulate the depth of the drop of the dipper, according to the depth of the ditch that is being dug.

I prefer also to provide sight gauges in connection with this cable controlling the 40 drop of the dipper, said gauges comprising bars 40, vertically movable in guides 41 on the boom and having cables 42 connected with the drum 34 and wound thereon simultaneously with the cable 35. A series of 45 pins 43 project horizontally from the bars 40 at different elevations, so that the operator of the machine can sight over these pins to the stakes, having similar pins for convenience in sighting, in front of the machine, which are set out by the engineers to 50 indicate the depth of cut of the ditch to obtain the desired fall and provide for the flow of water by gravity. By the operation of the worm control, the cable regulating 55 the depth of drop of the dipper and the gauge bars will be simultaneously adjusted and will work in unison in the operation of the machine.

A raising and lowering cable 44 is attached to the rear of the dipper and extends to a drum 45 that is loosely mounted on its shaft 64 near the loading drum 27. This drum has a driving connection 46 with a continuously operating shaft 47 driven by a 65 chain 48 from the drive shaft 28. A similar

drum 45^a is also loosely mounted on shaft 64 and has a driving connection 46^a with the shaft 47. Operation of these drums is controlled by a clutch 49 on the shaft 47 (see Figure 10, where this clutch is shown in 70 neutral position, with both drum stationary). A cable 50 connects the drum 45^a with the locking device of the dipper bottom.

I prefer to provide the drums 45 and 45^a with lugs 51 and 51^a, arranged so that one 75 drum may make one revolution independently of the other drum and then the lugs will come in contact with each other and the second drum will be revolved with the first one. By the adjustment of the clutch 49 the drum 45^a may be revolved one revolution 80 independently of the other drum to trip the dipper bottom, and then moved together, or the clutch may be moved in the other direction and power transmitted to the drum 85 45 to revolve both the drums in the first instance.

I will now proceed to describe the boom supporting track, which forms the principal part of my invention:

Referring to Figures 1 and 4, 52 represents a curved track, mounted at 53 on the forward rail of the main frame and having bolsters 54 seated on the side rails and secured by suitable means, such as bars 55. 95 This track 52 is preferably of I-beam construction and a carriage 56 is provided to slide longitudinally on the upper flange of the track, supported by wheels 57 and guided by suitable means, such as rollers 58. This 100 carriage is free to travel back and forth on the track following the curvature thereof and the arc of the circle (of which the pivot of the main boom is the center). At each 105 end the track is provided with safety stops 59. A frame 60 is mounted on the carriage 56 and projects upwardly therefrom and near its upper end has cross bars 61 adapted to enter notches 62 in the lower edge of the end extension 23 of the boom and form a 110 seat for the boom, the frame 60 supporting the weight of the outer end of the boom and the dipper and transmitting the load thereof to the carriage and the track beneath, thus relieving the opposite end of the machine from the function of counter-balancing the boom and bucket. Usually in machines of this type the rear portion of the machine has to be made sufficiently heavy or 115 weighted sometimes to counterbalance the tendency of the outer end of the boom and the bucket to tilt the machine. This naturally throws the weight to the rear and concentrates it at one point, making it difficult to move the machine over soft ground 120 and necessitating a heavier structure than is necessary for the work to be performed. With my machine the boom is supported at both ends, the rear portion may be made 125 much lighter, and in general the weight of 130

the machine can be distributed and the bearing points widely separated so that there is less tendency of the machine to sink into soft ground.

5 The use of the carriage supporting the outer end of the boom enables me to mount the track down close to the frame of the machine where it is unnecessary to brace it against racking and twisting to the extent 10 that would be necessary if the track were raised to a point opposite the normal position of the outer end of the boom. Furthermore, the use of the carriage permits tilting of the machine frame on uneven ground 15 without affecting the movement of the boom to the extent that it would be if the track were raised.

I prefer to provide two supporting bars 20 61 so that the elevation of the boom can be changed slightly, if desired, and the sheave 26 is made adjustable in the boom, as indicated in Figure 2.

The bucket supporting boom, as heretofore stated, is capable of horizontal movement on its pivot for the purpose of conveying the soil excavated by the bucket to a point outside the frame of the machine, as indicated by dotted lines in Figure 1, where it will be noted the bucket or dipper 30 and boom are indicated by full lines in the middle of the figure, while in dotted lines the dumping position of the bucket is indicated either to the right or left of the machine frame.

35 For oscillating the boom and bucket to these dumping positions, I provide drums 63 and 63^a, keyed to the shaft 64 on which the drums 45 and 45^a are loosely mounted. Cables 65 and 65^a are connected with the 40 drums 63 and 63^a, the former for swinging the boom to the left and the latter for swinging it to the right. The cables are oppositely wound on the drums, as shown plainly in Figures 1 and 10.

45 For operating these drums I prefer to provide the following described mechanism:

Referring to Figure 11, a gear 66 is mounted on the drum 63. A pinion 67 is secured on a shaft 68 and meshes with the 50 gear 66 to revolve the drums 63 and 63^a when power is applied to said shaft. A gear 69 is mounted on the shaft 47 and pinions 70 and 70^a are loosely mounted on said shaft and mesh with the gear 69 upon opposite sides of the shaft 47. Clutches 71 and 71^a are provided for locking the pinions 70 and 70^a alternately on the shaft 68. A sliding rod 72 is placed between the clutches 71 and 71^a so that when one is moved into its 55 clutching position, the other is disengaged to prevent engagement of both clutches at the same time. These oppositely arranged pinions and clutches are for the purpose of reversing the direction of movement of the 60 shaft 68 and the drums 63 and 63^a to wind

or unwind the cables. Clutch arms 73 and 73^a are provided and rods 74 and 74^a connect these clutch arms with arms 75 and 75^a mounted on shafts 76 and 76^a on the forward portion of the deck 9. These shafts extend 70 transversely of the machine and are provided with operating hand levers 77 and 77^a by means of which the operator of the machine can control the direction of revolution of the drums 63 and 63^a. 75

It is desirable in machines of this type to provide means for automatically operating the clutches 71 and 71^a to stop the boom when it reaches a point near the end of its supporting track. I, therefore, provide cables 78 and 78^a, the former connected with the arm 75 and the latter with the lever 77^a. These cables extend forwardly to bell cranks 79 and 79^a mounted on the underside of the track 52 and connected by links 80 with trip levers 81 and 81^a which project upwardly into the path of a bracket 82 on the frame 80 so that when the carriage reaches a predetermined point in its movement on the track this bracket will engage one of the 90 trip levers and actuate it to shift the clutch members 71 and 71^a and stop the drums 63 and 63^a. The cables 65 and 65^a engage the sheaves 83 on a sliding bar 84 mounted at the forward portion of the deck and have 95 running connections with sheaves 85, 86 and 87 mounted on the end portions of the curved track, and from thence past to sheaves 88 and are connected at 89 to the forward middle portion of the carriage, for 100 moving it and the boom supported thereby back and forth on the track as the cables are wound and unwound on the drums. Thus the operator of the machine may, by 105 the manipulation of the hand levers, control the lateral movement of the boom-supporting carriage or he may allow the outer movement to be automatically controlled by the trip levers and their connections with the drum controlling clutches. 110

In Figure 6 I have shown a machine adapted for digging tile trenches, or those where a tile is laid in the excavation and then covered, usually, as distinguished from the wider open ditches in the digging of 115 which the machine with the curved supporting track is used. The operation of the apparatus shown in Figures 6 and 7 is substantially the same as described with reference to the other figures, the curved track 120 being removed and the carriage supporting the boom resting and sliding upon the forward rail of the machine frame. When the machine is used in this way, the bucket is preferably unloaded or discharged on either 125 side of the narrow tile trench, as indicated by dotted lines in Figure 6, and there is sufficient room between the side rails of the frame to unload the bucket, as it is not necessary to deposit the excavated material 130

outside the frame, and hence the use of the track for guiding the carriage to a point beyond the sides of the frame is unnecessary. In other words, in digging narrow or 5 tile trenches, the curved track may be omitted, the forward portion of the boom being carried directly upon the frame of the machine, while in wide ditches, usually those of the open type, there is no room inside the 10 frame to deposit the excavated material, and hence the use of the track extending beyond the frame is desirable.

The forward traction supports of the main frame form the guiding means, and 15 to oscillate these supports on a vertical axis to steer the machine, I provide a bar 90 mounted to slide transversely of the machine in guides 91 and connected by rods 92 with the forward portions of the traction 20 belt frames. Cables 93 and 93^a are connected to the ends of the bar 90 and pass around sheaves 94 on the machine frame to a steering post and lever 95 mounted on the forward portion of the deck 9. (See Figures 25 1 and 6.) A bar 96 mounted to slide transversely of the deck 9 is connected by rods 97 with the frames of the rear traction belts, and one end of this bar has a rack 98 meshing with a pinion 99 on a steering post and 30 lever 100, also mounted on the forward portion of the deck 9, so that the operator of the machine can easily and quickly oscillate the rear supporting tractors to assist the 35 guiding of the machine.

35 The sliding bar 84 and the sheaves engaging the cables 65 and 65^a have the function of guiding these cables back and forth on their respective drums, the bar 84 moving transversely of the machine and being actuated through a belt 84^a and screw 84^b from the drum 63. (See Figure 1.)

I claim as my invention:

1. A ditching machine comprising a frame, a boom mounted at one end thereon, 45 a track having bearings on said frame and extending transversely thereof adjacent the rails of said frame whereby said track is rendered more stable and bracing is avoided, a carriage mounted on said track on a 50 level with the lower portion of said boom, means mounted on said carriage and projecting upwardly therefrom and having a support for the upper end of said boom, and means for moving said carriage on said 55 track from side to side of said frame.

2. A ditching machine comprising a frame, a boom mounted to swing laterally thereon, an excavating bucket carried by said boom, a carriage having a support for the 60 upper end of said boom, a track arranged transversely of said frame and having end sections projecting outwardly beyond the side rails of said frame a sufficient distance to allow said carriage to be moved outwardly 65 on said track to points outside the side

rails of said frame and said excavating buckets to be discharged of its contents in the space between said frame and the end sections of said track.

3. A ditching machine comprising a 70 frame, a boom mounted to swing laterally thereon, an excavating bucket carried by said boom, a carriage having a support for the upper end of said boom, a track for said carriage arranged transversely of said 75 frame and having end sections projecting outwardly beyond the side rails of said frame a sufficient distance to allow said carriage to be moved outwardly on said track to points outside the side rails of said frame and said excavating bucket to be discharged of its contents in the space between said frame and the end sections of said track, said track and carriage being located on a level with the lower portion of said 80 boom and adapted to support the upper or outer end thereof.

4. The combination, with a rectangular frame having supporting traction means at the corners thereof, of a boom mounted at 90 one end on the rear portion of said frame and overhanging the forward portion to swing laterally, a curved track removably mounted on the forward portion of said frame, on a level with the lower portion of said boom, a carriage to travel on said track having upwardly projecting means for supporting the forward end of said boom, said carriage when said track is removed being adapted to run on the forward rail of said 95 frame, and an excavating bucket carried by 100 said boom.

5. In a ditching machine, a frame, a boom supported on the rear of said frame, an excavating bucket carried by said boom, a carriage mounted on the forward portion of said frame for lateral movement thereon, a frame projecting upwardly from said carriage and having a seat thereon to receive and support the forward end of said boom, 105 said boom being mounted for vertical adjustment on said carriage frame.

6. A ditching machine comprising a frame, rectangular substantially in form, and having a deck at its rear end and a 110 curved track at the forward end of said frame projecting laterally beyond the side rails thereof, a carriage mounted to travel on said track and a boom supported at its rear end on said deck and having its forward end supported by said carriage to move laterally therewith, and an excavating bucket carried by said boom, said track being removable from said frame to allow said carriage to be supported and operated on 115 the forward rail of said frame.

7. A machine of the class described comprising a frame, a curved track mounted on one end of said frame and having its ends 120 extending outwardly beyond the side rails 125

of said frame, a carriage mounted to move back and forth on said track and having an upwardly projecting frame, cables attached to the lower portion of said carriage and 5 having running connections with the outer ends of said track, drums whereon said cables are wound for moving said carriage back and forth on said track, a boom mounted at one end on said frame and having 10 its opposite end supported by the upwardly projecting frame of said carriage, and an excavating arm and bucket mounted in said boom, said carriage, boom, and bucket being moved to bucket discharging points 15 outside said machine frame upon opposite sides thereof.

8. A ditching machine comprising a frame, a boom mounted at one end thereon, a curved track supported on the forward 20 portion of said frame on a level with the lower portion of said boom, a carriage comprising rails having wheels to rest and travel on said track, a frame supported by said carriage rails and projecting upwardly 25 therefrom, and having means connected with said carriage, and with a source of power for moving said carriage forward and backward on said track, and an excavating bucket supported by said boom.

9. A ditching machine comprising a frame, a boom mounted at one end thereon, a track mounted on said frame and extending from side to side thereof, a carriage having antifriction bearings on said track and 30 movable thereon from one side of the machine to the other, said carriage being on a level with the lower portion of said boom, means mounted on said carriage and projecting upwardly therefrom and having a support for the upper end of said boom, and means for moving said carriage on said track from side to side of said frame.

10. A ditching machine comprising a frame, a boom mounted at one end thereon, 40 a track provided at the other end of said frame, a carriage mounted to travel on said

track on a level with the lower portion of said boom, means for moving said carriage forward and backward on said track, a frame projecting upwardly from said carriage, cross-bars mounted in said frame upon different levels, and adapted to support the upper end of said boom, and for changing the vertical adjustment of said boom on said frame, and an excavating 55 bucket mounted in said boom.

11. A ditching machine comprising a frame, a boom mounted at one end thereon, a track mounted on said frame, a carriage having bearings on said track opposite and 60 on a level with the lower portion of said boom, means for moving said carriage forward and backward on said track, levers for controlling the operation of said moving means, a frame mounted on said carriage 65 and projecting upwardly therefrom and having a support at its upper end for the outer end of said boom, a bracket mounted on the lower portion of said frame in position to engage and actuate said levers when 70 said carriage reaches a predetermined point on said track, and an excavating bucket mounted in said boom.

12. A ditching machine comprising a frame having side and end rails, a boom 75 mounted at one end on the rear portion of said frame, a curved track mounted on the forward rail of said frame and having bolsters seated on said side rails and secured thereto, said track being in the form of an 80 I-beam and a carriage having wheels to slide on the upper flange of said beam and provided with suitable guiding rollers, means for moving said carriage forward and backward on said track, a frame mounted on said 85 carriage and projecting upwardly therefrom and whereon the upper end of said boom is seated, and an excavating bucket carried by said boom.

In witness whereof I have hereunto set my 90 hand this 25th day of February, 1922.

LOUIS H. LARSON.
